(74) Attorney, Agent, or Firm — Carter, DeLuca,
Farrell & Schmidt, LLP(57) **CLAIM**

The ornamental design for a dual purpose grill, as shown and described.

DESCRIPTION

FIG. 1 is a front perspective view of a dual purpose grill in accordance with the present design;

FIG. 2 is a front side elevational view thereof;

FIG. 3 is a rear side elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a front perspective view of the dual purpose grill in an open configuration;

FIG. 9 is a front side elevational view thereof;

FIG. 10 is a rear side elevational view thereof;

FIG. 11 is a right side elevational view thereof;

FIG. 12 is a left side elevational view thereof;

FIG. 13 is a top plan view thereof; and,

FIG. 14 is a bottom plan view thereof.

The broken lines shown in the drawings illustrate portions of the dual purpose grill that form no part of the claimed design.

1 Claim, 14 Drawing Sheets(56)
